ELECTRICAL CONNECTION MEANS

Alois L. Martinek, Bronson, Mich., assignor to
 Kingston Products Corporation, Kokomo, Ind.,
 a corporation of Indiana

Application June 21, 1937, Serial No. 149,513

4 Claims. (Cl. 173—328)

This invention relates generally to electrical connection means and more particularly has to do with means adapted to receive and retain terminals of the snap type.

One object of the invention is to provide an arrangement including a plate of insulating material; a shell secured thereto and provided with a concave seat adapted to accommodate a terminal of the snap type, and an aperture in the seat through which terminal receiving means extend for holding and pressing a terminal against said seat.

Another object of the invention is to form the seat in the shell and the terminal receiving means in such a manner whereby to provide a cylindrical receiving aperture.

Another object of the invention is to provide means operatively related to the shell and extending therefrom whereby a conductor may be secured thereto.

A further object of the invention is to provide a durable device which is comprised of very few parts, which may be easily and quickly assembled and manufactured economically on a commercial scale.

Many other objects and advantages of the invention herein disclosed will be apparent after considering the description hereinafter set forth in connection with the drawing annexed hereto, wherein the parts of the electrical connection means are designated by numerals.

Referring to the drawing:

Figure 1 is a vertical section of one embodiment of the invention;

Figure 2 is a section taken substantially on line 2—2 of Figure 1;

Figure 3 is a section taken substantially on line 3—3 of Figure 2;

Figure 4 is a vertical section of another embodiment of the invention;

Figure 5 is a vertical section taken substantially on line 5—5 of Figure 4;

Figure 6 is a section taken substantially on line 6—6 of Figure 5;

Figure 7 is a vertical section of another embodiment of the invention;

Figure 8 is a vertical section taken substantially on line 8—8 of Figure 7; and

Figure 9 is a section taken substantially on line 9—9 of Figure 8.

Referring to the embodiment of the invention disclosed in Figures 1 through 3 of the drawing, 1 represents a plate of insulating material upon which is mounted the electrical connection means. The electrical connection means is com-

prised of a metallic shell 2, terminal receiving means 3, resilient means 4, and an extension 5. The upper extremity 6 of the shell 2 is preferably depressed so as to provide a semi-cylindrical groove or seat 7 which is adapted to accommodate the terminal shown. An aperture 8 preferably of rectangular formation is provided intermediate the ends of the seat 7, and the terminal receiving means 3 extends therethrough transversely to the seat 7.

Any form of means may be provided for pressing and holding a terminal of the character shown against the seat 7, but as here shown, the means preferably employed for this purpose is in the form of an inverted U, comprised of spaced apart legs 9 joined adjacent their upper extremities by a loop portion 10. The loop portion 10 is preferably of the same curvature as the seat 7 so that together they form a cylindrical terminal receiving aperture. The loop 10 is provided with a detent portion 11, adapted to cooperate with the cove 12 in the terminal. The lower extremity of each of the legs 9 is provided with a sectoral flange 13, the purpose of which will appear later. Rotation of the means 3 is prevented since it extends through the aperture 8 in the shell.

The resilient means 4, which is in the form of a helical compressible spring, is arranged within the confines of the shell 2, and encircles the terminal receiving means 3, with one end engaging the underside of the seat 7, and the other end the flanges 13. Through the agency of this spring, the terminal receiving means 3 is normally held in abutting relation with the extension 5 prior to the insertion of a terminal in the terminal receiving aperture. When a terminal is being inserted in the terminal receiving aperture, the terminal receiving means 3 is moved outwardly against the tension of the spring 4, and when the terminal is properly located in the seat 7, the spring will press and draw the spaced apart lands 14 on the terminal against the seat 7, and the detent 11 will hold the terminal in place.

The electrical connection means may be connected to the plate 1 in different ways, but as here shown, the parts are preferably constructed in such a manner that they can be assembled together in only one way.

The extension 5, as here shown, is preferably constructed of sheet metal folded back upon itself, and the upper extremity thereof is provided with a pair of outwardly extending substantially semi-circular flanges 15 and 16 oppositely arranged in the same plane. As clearly

shown in Figure 3, the flange 15 is provided with a relatively small notch 17, and the flange 16 with a pair of spaced apart notches 18 of a slightly greater circumferential extent than notch 17. The flanges 15 and 16 are adapted to rest upon the plate 1 with the extension 5 projecting through a rectangular aperture 24 in the plate 1. The lower extremity of extension 5 may be provided with an aperture 25 through which an electrical conductor may be inserted and suitably secured.

The lower extremity of the cylindrical shell 2 is preferably provided with an outwardly extending annular base flange 19. This flange is provided with a small finger or continuation 20, and a pair of larger fingers or continuations 21, and as clearly shown, these fingers project through the notch 17, and the notches 18, respectively.

The arrangement is such that the notch 17 can only accommodate the finger 20. Thus, it will be evident that the extension 5 and the shell 2 can only be arranged in one predetermined relation with respect to each other, and that the terminal receiving means 3 is arranged in a predetermined relation with respect to the shell 2. An arcuate aperture 22, and a pair of arcuate apertures 23 are arranged circumferentially about the rectangular aperture 24 in the plate 1. The aperture 22 is smaller than either of the apertures 23 so as to accommodate the small finger 20 formed on the shell, and the apertures 23 are adapted to receive the pair of fingers 21. These fingers are projected through their respective apertures, and are clinched outwardly against the lower surface of the plate 1 in the manner shown. Since the aperture 22 can only receive the finger 20, the parts can be assembled in only one position upon the plate 1.

As above referred to, the shell and the extension 40 can be assembled together in only one relative position, and although this is desirable in most instances, it is to be understood that if found desirable, the flanges 15 and 16 adjacent the upper extremity of the extension 5, may be made 45 smaller in size and without notches so as to fit within the space defined by the fingers 20 and 21, in which event the rectangular aperture 24 will predetermine the position of the extremity 5. In other words, the particular type of connection 50 between the flanges 15 and 16 and the fingers 20 and 21 may be omitted.

Referring to the embodiment of the invention disclosed in Figures 4 through 6, the arrangement is substantially the same as above described, except that all of the metal parts are secured together as a unit before assembly with a plate or disc of insulating material.

In this embodiment, the upper extremity of the extension 30 is provided with substantially semi-cylindrical portions 31 and 32, having notches therein corresponding to those disclosed in Figure 3, and in addition, the portion 31 is provided with a pair of spaced apart notches 33, and the portion 32 with a notch 34. As clearly shown, 60 the annular base flange adjacent the lower extremity of the shell is provided with a pair of fingers 35, and a finger 36 equidistantly spaced from each other. The pair of fingers 35 are adapted to project through the pair of notches 70 33, and the finger 36 through the notch 34, and are clinched inwardly as indicated at 37 against the under surface of the portions 31 and 32. Thus the shell, terminal receiving means, resilient means, and the extension are assembled together to 75 constitute a unit that is in turn adapted

to be mounted on a plate of insulating material. The annular flange on the shell is also provided with a plurality of fingers corresponding to the fingers shown in Figure 3, and these fingers are arranged between the fingers 35 and 36, and are projected through apertures provided in the plate after the parts are assembled as a unit as aforesaid. The fingers 35 and 36, as clearly shown in Figure 5, are adapted to rest and bear against the upper surface of the plate or disc. 10

Referring to the embodiment of the invention disclosed in Figures 7 through 9, the primary object is to omit a separate extension, and provide the shell with an integral extension. As here shown, the annular flange 40 on the shell 41 is 15 provided with an offset depending extension 42 which projects through an aperture 43 provided in the insulating plate 44. The annular flange 40 is also provided with a pair of offset fingers 45 diametrically arranged, which project through a 20 pair of apertures 46, diametrically arranged, in the insulating plate 44 and are clinched inwardly against the lower surface of said plate.

It is to be understood that the metal parts in this embodiment can also be assembled together 25 as a unit as disclosed in Figures 4 through 6.

In view of the foregoing, it will be evident that an improved electrical connection is provided whereby to resiliently detachably retain a terminal of the snap type, and that the terminal receiving means functions to press the terminal against the shell so that the current travels to the extension through the shell. 30

Having thus described my invention, it is obvious that various immaterial modifications may be made in the same without departing from the spirit of the invention; and therefore, I do not wish to be understood as limiting myself to the exact forms, constructions, arrangements, and combination of parts, herein shown and described. 35

What I claim and desire to secure by Letters Patent is:

1. Electrical connection means including in combination, a support of insulating material 45 provided with an aperture, a shell secured to said support and provided with a concave seat and an opening intermediate the ends of said seat, terminal receiving means extending through said opening transversely to said seat to a position 50 maintaining said receiving means normally open to receive a terminal, resilient means operatively related to said receiving means whereby to press a terminal of the snap type inserted into said receiving means against said seat, means engaging said terminal receiving means and extending through the aperture in said support providing an extension to which an electrical conductor may be connected, said extension being provided with notches and said shell with fingers 60 projecting through said notches, the arrangement of said notches and fingers being such that said extension can be assembled with said shell in a predetermined position.

2. Electrical connection means including in 65 combination, a support, and a pair of sheet metal complementary members, one of said members being fixedly secured to said support and having an opening receiving the other member and an exterior bearing surface for a terminal, abutment 70 means provided on said support within the confines of said one member, said other member having a terminal receiving aperture and being slidable in said opening to normally engage said abutment means to maintain said aperture in a 75

predetermined position with respect to said bearing surface whereby said member will slide outwardly with respect to said surface solely by the insertion of the terminal within said aperture.

5 3. Electrical connection means including in combination, a support, a pair of sheet metal complementary members, and resilient means, one of said members being fixedly secured to said support and having an opening receiving the 10 other member and an exterior bearing surface for a terminal, abutment means provided on said support within the confines of said one member, said other member having a terminal receiving aperture and being slidably in said opening to 15 normally engage said abutment means to maintain said aperture in a predetermined position with respect to said bearing surface whereby said member will slide solely by the insertion of a terminal within said aperture, said resilient 20 means acting to return said other member to engage said abutment means upon the removal of said terminal.

4. Electrical connection means including in combination, a plate of insulating material, abutment means provided on said plate, a metal shell having a bearing surface secured to said plate, an aperture provided adjacent said bearing surface, an arched sheet metal member slidably arranged in said aperture, said member having a terminal receiving opening adjacent its arched end, the length of said member being such that when said member engages said abutment means 5 said opening is so positioned with respect to said bearing surface that when a terminal of the plug conductor type is inserted into said opening said member is bodily displaced with respect to said shell without first adjusting said member to receive said terminal, and resilient means for normally holding said member in engagement with said abutment means.
